UNITED STATES PATENT OFFICE.

JOHN B. LOCKWOOD, OF HELMVILLE, MONTANA.

CLOTHES-PIN.

SPECIFICATION forming part of Letters Patent No. 490,971, dated January 31, 1893.

Application filed May 20, 1892. Serial No. 433,665. (No model.)

To all whom it may concern:

Be it known that I, JOHN B. LOCKWOOD, of 5
Helmville, in the county of Deer Lodge and
State of Montana, have invented a new and
useful Improvement in Clothes-Pins, of which
the following is a full, clear, and exact de-
scription.

My invention relates to an improvement in
clothes pins, and has for its object to construct
10 a clothes pin upon the pincher type, and to
construct the pin in such manner that it may
be locked upon a line or unlocked therefrom
conveniently and expeditiously with one
hand. And a further object of the invention
15 is to provide a locking mechanism in connec-
tion with the body of the pin, whereby when
said mechanism is brought into operation the
jaws of the pin will be firmly held in a locked
position, from which they can depart only
20 when the locking device has been properly re-
leased from its locking engagement with the
body.

The invention consists in the novel con-
struction and combination of the several parts,
25 as will be hereinafter fully set forth and point-
ed out in the claim.

Reference is to be had to the accompanying
drawings forming a part of this specification,
in which similar figures and letters of refer-
30 ence indicate corresponding parts in all the
views.

Figure 1 is a side elevation of the improved
clothes pin, illustrating the jaws in an open
position; Fig. 2 is a view taken from the op-
35 posite side of the pin, illustrating the jaws in
their closed position, and the locking mech-
anism in locking engagement with the pin;
and Fig. 3 is a transverse section taken prac-
tically on the line 3—3 of Fig. 2.

40 The body of the clothes pin comprises two
sections A and B. These sections are pivot-
ally connected preferably between their cen-
ters and their lower ends. The sections cor-
respond practically to the sections of a pair
45 of pinchers, and the section A, is provided with
a diagonal recess 10, in one face, adapted to
enter a corresponding recess 11 in the oppo-
sing face of the opposite section B. The
recesses are made diagonal in order that the
50 movements of the sections upon each other
may be limited without the assistance of added
stops of any description. Each section is

shaped at its lower end in a manner to form
a jaw, the jaw of the section B, being design-
ated by the reference numeral 11^a, and the 55
jaw of the section A by the reference numeral
12; and by recessing the body of the mem-
bers in the manner above described, the two
jaws are made to face one another in such
manner that they may close around a line and 60
that portion of an article lying over the line.
To that end the jaws are semi-circular in gen-
eral contour and their concaved surfaces face
each other, producing a circular opening be-
tween the jaws when said jaws are in their 65
closed position.

The main feature of this invention lies in
the locking mechanism, and this is located at
the upper or handle ends of the sections A 70
and B. The handle portion of the section B,
is provided at a predetermined distance from
its extremity with a shoulder 13 transversely
located; the said shoulder, however, is not ex-
actly at a right angle to the section, but is 75
given somewhat of an upward inclination.
From the inner portion of the shoulder the
outer edge of the handle section B, is ren-
dered curved, forming thereby a cam face 14,
as is best and clearly shown in Fig. 1. This 80
cam face extends from the shoulder to and
constitutes a portion of the extremity of this
section. Upon the handle extremity of the
section A of the pin a latch 15, is pivoted.
This latch is substantially of yoke formation, 85
as is shown in Fig. 3, and usually consists of
a block in which a slot 16, is longitudinally
produced, extending through and from one
end; and this yoke latch is pivoted to the sec-
tion A, near the end through which the slot 90
16 extends. The yoke latch is so located upon
the section A that when the two sections A
and B, are carried inward or in direction of
each other in such manner as to carry the
jaws 11^a and 12 as far as possible together, 95
by passing the yoke latch downward the han-
dle extremity of the section B will enter the
slot 16 in the latch, and the cam surface 14,
will be brought to a binding engagement with
the end wall of the slot, as shown in Fig. 2. 100
This engagement practically locks the jaws
11^a and 12 in their closed position; but in or-
der that greater security in the way of a lock
may be obtained the latch is forced farther
downward until it is brought to an engage-
ment.

ment with the shoulder 13, at which time it will be in a diagonal position with respect to the two sections A and B, and the cam surface will be in most effective frictional engagement with the end wall of the slot 16, while the under face of the latch will be in frictional engagement with the shoulder 13, and the diagonal position of the latch in addition to its frictional engagement with the body of the pin will effectually prevent the latch from becoming disengaged, or coming to an unlocking position unless considerable pressure is exerted upon that portion of the latch extending beyond the cam surface of the body; and the object of extending the latch beyond the cam surface is in order that this portion of the latch may be readily engaged by the thumb of the operator's hand while with his fingers the body of the pin is grasped. It will thus be observed that this device is not only simple, economic, durable and capable of ready manipulation, but that it may be manipulated by the operator with but one hand, leaving the other hand free to dress the clothes upon the line, and that by locating the shoulder 13 and placing the cam face 14 in the position in which they have been shown and described, the latch may be carried diagonally downward over the body, thereby insuring a much more firm and positive lock

than could be obtained by placing the latch transversely, when in the locking position, or giving it an upward inclination.

Having thus described my invention, I claim as new and desire to secure by Letters Patent,—

As an article of manufacture, a clothes pin, the same consisting of two members pivotally connected, each section having one end shaped as a handle and the other as a clamping jaw, the jaws being curved in direction of each other, the said sections being also provided with opposing diagonally located recessed surfaces whereby the jaws are brought face to face and their movement outward and inward limited, a cam surface produced upon the outer face of the handle portion of one section, this section being also provided with a shoulder at the base of the cam surface, and a latch pivoted to the handle portion of the opposite section, the latch comprising a block provided with a recess to receive the cam surface above mentioned, which latch is diagonally located across the section when in locking position and engaged with the said shoulder, substantially as and for the purpose set forth.

JOHN B. LOCKWOOD.
